ANTENNA CONSTRUCTION

Mikhail Samoilovich Neiman, Leningrad, Union of Soviet Socialist Republics, assignor to Radio Corporation of America, a corporation of Delaware

Application May 7, 1940, Serial No. 333,846. In
Union of Soviet Socialist Republics March 10,
1938

6 Claims. (Cl. 250—33)

This invention relates to a new and useful antenna construction.

An object of this invention is to provide a system to feed energy at any point on the antenna by a shielded feeder terminating in the form of a coupling device, which may provide either magnetic or capacitive coupling.

Another object of this invention is to measure the antenna energy at any point and to obtain anti-fading or general directive qualities in a vertical plane with an antenna much reduced in height by comparison with the wave length and also to obtain an optional distribution in phase and amplitude for the currents in the antenna so as to secure the most favorable radiation diagram.

Another object of this invention is to measure energy at any point to obtain a periodic, continuous or automatic check of the distribution of currents in various parts of the antenna, or to provide signals indicating deviations from the normal.

A further object of this invention is to effectively tune the antenna from the transmitter building.

A still further object of this invention is to tune the upper antenna elements to control the distribution of currents from ground or from the transmitter building.

A still further object of this invention is to provide means for feeding energy to the antenna at several points.

Some of the many other objects of this invention are to provide an antenna system to eliminate the harmful effect of traveling waves along the antenna mast and to widen the frequency band of anti-fading antennas, as well as other antennas, also, to provide an anti-fading antenna suitable for operation on a certain wave range.

In order to attain these objects, I propose an antenna the construction of which can be most readily understood by referring to the accompanying drawing, in which:

Fig. 1 shows one form of antenna construction of this invention;

Fig. 2 is a diagram showing the electro-magnetic oscillations in the antenna;

Fig. 3 is another modification of the invention wherein the antenna is tuned from the ground;

Fig. 4 is another modification of the invention showing a single turn coupling coil;

Fig. 5 is another modification of the invention showing a toroid shaped coil; and

Fig. 6 is another modification of the invention showing a measuring method.

Referring now in detail to Fig. 1 of the drawing, 1 is the vertical mast or tower of the antenna, 2 a shielded feeder which includes two insulated leads and which runs from an oscillation source 4 at first on the ground and then along the mast, the leads then terminating at a certain height in a coil 3 made up of one or several turns or windings of any desired shape. The preferred position of the axis of the coil is horizontal to and at ninety degrees with respect to the axis of the antenna.

The exterior surface of the metallic shielded feeder 2 is attached without any insulation directly to the metal of the antenna mast, thus constituting, in an electrical sense, a common body. As far as the inner part of the shielded feeder is concerned, it is not electrically connected with the antenna proper except for the magnetic coupling which is effected by the coil 3. This constitutes the useful coupling which can be utilized in two ways: for example, on one hand by having the radio frequency generator 4 connected to the lower end of the feeder which will produce in the antenna electro-magnetic oscillations as a result of the coupling (which may be if desired either inductive or capacitive) between the coil and the structure of the tower. Thus, a possibility of feeding the antenna is provided. As shown by Fig. 2, the action of the generator may in this case be replaced by an equivalent electromotive force applied at the point where the coil 3 is located.

On the other hand, if the antenna is fed by some other electro-motive force, one may connect to the lower end of the feeder 2 a measuring instrument 7, for instance, an ammeter, which could be utilized to measure the instantaneous current in the antenna at the point where the coil 6 is located, i. e., at any height above the ground, as shown by Fig. 3.

Obviously, it is possible to attach several feeders to one antenna tower. In that case, the feeding could be accomplished by means of a corresponding number of electromotive forces arranged in any manner desired along the antenna. The amplitudes and phases of these electromotive forces may also be fixed at random by means of suitably selected coupling elements. All feeders may be supplied either by a single generator or by several generators. Furthermore, it is evident that the current could be measured at any number of points along the antenna, which makes it possible to have at hand in the trans-

mitter building a variety of currents and voltages corresponding to the actual current distribution at different points in the antenna. These currents and voltages could readily be utilized as a periodic or continuous check on the performance of the antenna, for the purpose of tuning, for example, by means of a condenser, or of indicating deviations from normal operating conditions.

Let us bear in mind that, according to theory, an arbitrary distribution of electromotive forces along the antenna produces an equally arbitrary distribution of currents in the antenna. Under such conditions, it becomes possible to obtain any desired radiation diagram (for instance, one markedly flattened toward the horizon) with an antenna of any height. Obviously, a reduction in height of the antenna renders the actual construction of such an antenna more difficult inasmuch as the number and intensity of the electromotive forces must increase accordingly. Therefore, practical considerations impose certain limits in this respect. However, by comparison with ordinary antenna types, the proposed construction offers certain decided advantages regarding both the reduction in height of the antenna and the effectiveness of the radiation diagram.

We observe further that by a proper selection of the coupling elements between the generator and the coils located at different heights along the antenna, it is possible to obtain relatively different changes in the amplitude and phase of these electromotive forces for any change in frequency of the generator. This fact can be utilized to extend the frequency band of the antenna or to improve the frequency characteristics.

It is necessary to point out also that this invention enables the operator to tune the antenna from the ground. For a better understanding of this feature, let us refer to Fig. 3. Here, 5 is a coil which feeds the antenna, 6 is a coil supplying a certain electromotive force e . If we make the phase of the current I in the coil 6 such that the electromotive force e is in a phase quadrature relationship with the antenna current I_A at the point of location of the coil 6, then the effect of this electromotive force is equivalent to providing at this point an inductance L in series, given by

$$j\omega L = \frac{e}{I_A} = j\omega M \frac{I}{I_A}$$

or

$$L = M \frac{I}{I_A}$$

Therefore, by varying the amplitude of the current I in the coil by changing, for instance, in the transmitter building the coupling between the feeder that supplies it and the generator, we are able to change the value of the equivalent inductance provided in the upper part of the antenna. Thus, the changing of this inductance, i. e., the tuning of the antenna, may be accomplished from the ground.

This feature also makes it possible to utilize an antenna for any wave within the wave range without the necessity of climbing the antenna every time the length of the operating wave is changed.

Obviously, this invention is applicable not only to tower antennas but to any other type of antennas, for instance wire- or hollow-pipe antennas. Likewise, due to the reciprocal principle, this invention is equally applicable to receiving antennas, only that in this case, the coupling

elements to the generator are replaced with corresponding coupling elements to the receiver and with proper phasing elements.

Let us note, furthermore, that in some cases (for instance in the case of wire antennas) it may prove more convenient to couple the coils at the ends of the feeders, not to the straight antenna wire or to the body of the tower but to an additional coil in series with the antenna wire.

Moreover, for the purpose of reducing the number of shielded feeders required, it is feasible to secure the coupling between the transmitter or receiver on one hand and all the coupling coils or a group of these coils on the other hand by way of common shielded feeders. In this case, the shielded feeder must extend to the most distant coil (for instance, the highest), while at the location of the other coils the feeder is tapped (parallel, in series or in some other way).

Similarly, when vacuum tube voltmeters or rectifiers such as 9 are used in measuring the current, the wires connecting the various meters may be combined into a common shield or cable. The return wires may also be combined.

The coupling coils may be of various construction. They may be built in the form of single-turn 10 as shown by Fig. 4 or multiple-turn loops attached directly to the tower or mast.

One may also apply, though this is not likely to be necessary in the majority of cases, various electrostatic shields (for instance, in the shape of a split pipe shield concentric with the coupling coil). As shown by Fig. 5, a convenient shape of coil 11 may be a toroid surrounding the antenna conductor.

Now, in addition to the foregoing, let us consider another method of feeding the antenna. If the main conductor of the antenna is provided with a branch (for instance, in the shape of a horizontal wire), then by coupling the coil at the end of the feeder to this wire, we obtain another coupling, in the manner explained above. In the main conductor of the antenna, there will then be a drop in current, not in voltage, as a result of the current deflected into the branch. As shown by Fig. 6, one lead 12 is conductively connected to the mast 1 of the antenna tower and the other lead 13 left free therefrom. If the lower end of the feeder is connected to a measuring instrument, instead of being connected to the generator, the meter 14 will register the voltage in the antenna, not the current. Thus, it becomes possible to measure both the current and the voltage at any point along the antenna.

What is claimed is:

1. An antenna system comprising an antenna member electrically connected to ground at the base portion thereof, a plurality of metallic shielding members located at the base portion and arranged so as to follow up along a portion of the sides of said antenna member and electrically connected thereto, a pair of insulated leads located within each one of said metallic shielding members, a plurality of coupling coils, each coil located near the upper and open end of said metallic shielding members and inductively coupled to said antenna member at a voltage node, each of said leads connected at one end to said coupling coils and at the other end to a transmitting source of energy, and measuring means for measuring the transmitting energy at several points along the antenna member.

2. An antenna system comprising an antenna member electrically connected to ground at the base portion thereof, a plurality of metallic

shielding members located at the base portion and arranged so as to follow up along a portion of the sides of said antenna member and electrically connected thereto, a pair of insulated leads located within each one of said metallic shielding members, a plurality of coupling coils, each coil located near the upper open end of said metallic shielding members and inductively coupled to said antenna member at a voltage node, each of said leads connected at one end to said coupling coils and at the other end to a transmitting source of energy, and means for tuning the antenna from the point of source of the transmitting energy.

3. An antenna system comprising an antenna member electrically connected to ground at the base portion thereof, a plurality of metallic shielding members located at the base portion and arranged so as to follow up along a portion of the sides of said antenna member and electrically connected thereto, a pair of insulated leads located within each one of said metallic shielding members, a plurality of coupling coils, each coil located near the upper open end of said metallic shielding members and inductively coupled to said antenna member at a voltage node, each of said leads connected at one end to said coupling coils and at the other end to a transmitting source of energy, and means for tuning the antenna by having the voltage out of phase at different lengths of leads to said antenna coupling coils.

4. A radio frequency system comprising a radiating member electrically connected to ground at the base portion thereof, a plurality of shielding members located at the base portion and arranged to follow up along a portion of the side of said radiating member and electrically connected directly thereto, at least one insulated lead located within each one of said shielding members, each shielding member having an open end located at different levels above ground, a coupling element located near the upper end of each one of said shielding members, each coupling element coupled to said radiating member, each one of said insulated leads arranged in circuit connection with said coupling element and said radio frequency device whereby optional distri-

bution in phase and amplitude for the currents in said radiating member is obtained to secure the most favorable radiation diagram.

5. A radio frequency system comprising a radiating member electrically connected to ground at the base portion thereof, a plurality of shielding members located at the base portion and arranged to follow up along a portion of the side of said radiating member and electrically connected directly thereto, at least one insulated lead located within each one of said shielding members, each shielding member having an open end located at different levels above ground, coupling means located near the upper end of each one of said shielding members for obtaining a desired distribution of current in said radiating member, each coupling element arranged for electrically coupling to said radiating member, each one of said insulating leads arranged in circuit connection with said coupling element and a radio frequency device whereby optional distribution in phase and amplitude for the currents in said radiating member is obtained to secure the most favorable radiation diagram.

6. A radio frequency system comprising a radiating member electrically connected to ground at the base portion thereof, a plurality of shielding members located at the base portion and arranged to follow up along a portion of the side of said radiating member and electrically connected directly thereto, at least one insulated lead located within each one of said shielding members, each shielding member having an open end located at different levels above ground, coupling means located near the open end of each one of said shielding members for obtaining a desired distribution of current in said radiating member, each coupling element arranged for electrically coupling to said radiating member, each one of said insulating leads being arranged in circuit connection with said coupling element and radio frequency device, and rectifying means located adjacent the open end of at least one of said shielding members and connected to at least one of the insulated leads contained within said shielding members.
